(57) **CLAIM**

The ornamental design for an oscillatory drive, as shown and described.

DESCRIPTION

FIG. 1 is a side elevational view of an oscillatory drive showing our new design;

FIG. 2 is an opposite side elevational view of the oscillatory drive of FIG. 1;

FIG. 3 is a top perspective view of the oscillatory drive of FIG. 1;

FIG. 4 is a bottom plan view of the oscillatory drive of FIG. 1;

FIG. 5 is a top plan view of the oscillatory drive of FIG. 1;

FIG. 6 is a rear end view of the oscillatory drive of FIG. 1; and,

FIG. 7 is a front end view of the oscillatory drive of FIG. 1.

1 Claim, 7 Drawing Sheets

FIG. 4

FIG. 5

FIG. 6

FIG. 7

UNITED STATES PATENT AND TRADEMARK OFFICE
CERTIFICATE OF CORRECTION

PATENT NO. : Des. 511,284 S
DATED : November 8, 2005
INVENTOR(S) : Heinrich Henssler et al.

Page 1 of 1

It is certified that error appears in the above-identified patent and that said Letters Patent is hereby corrected as shown below:

Title page.

Item [73], Assignee, should read -- **C. & E. Fein GmbH (DE)** --.

Signed and Sealed this

Seventh Day of March, 2006

A handwritten signature in black ink, appearing to read "Jon W. Dudas". The signature is written in a cursive style with a large, stylized "J" and "W".

JON W. DUDAS
Director of the United States Patent and Trademark Office
